UNITED STATES PATENT OFFICE.

LOUIS E. TESTER, OF SACRAMENTO, CALIFORNIA.

HYDROCARBON-BURNER.

1,299,263.

Specification of Letters Patent.

Patented Apr. 1, 1919.

Application filed April 13, 1918. Serial No. 228,353.

To all whom it may concern:

Be it known that I, LOUIS E. TESTER, a subject of Great Britain, residing at Sacramento, in the county of Sacramento and

5 State of California, have invented certain new and useful Improvements in Hydrocarbon-Burners; and I do declare the following to be a clear, full, and exact description of the same, reference being had to the accompanying drawings, and to the characters of reference marked thereon, which form a part of this application.

This invention relates to improvements in hydrocarbon burners. The object of the invention is to produce a burner of the type described which will permit the fuel to be gasified in such a manner and to such a degree as to eliminate carbon deposits being formed within the gasifying retort or in the 20 gas pipe and discharge outlet leading therefrom. In most of the present day types of hydrocarbon burners, the retorts are so constructed and so subjected to an intense heat that carbon forms within the retort and then 25 cakes both in the retort and in the outlet pipes and discharge jets leading therefrom. These objectionable features I aim to entirely do away with.

From long experimentation I have discovered that in order to produce a perfect burner of the type here claimed, it is necessary to first heat the fuel to the point of vaporization, but not beyond such point, and then allow it to come into contact with 35 plenty of oxygen prior to its being burned. By so heating it the vaporized fuel in the retort retains its chemical composition without breaking up into its elements, thus preventing free carbon from being deposited in 40 the retort and the outlet therefrom.

This I have done in my improved burner and retort, and have eliminated the use of excessive temperature and back pressure in the retort.

45 A further object of the invention is to produce a simple and inexpensive device and yet one which will be exceedingly effective for the purposes for which it is designed.

50 These objects, I accomplish by means of such structure and relative arrangement of the parts as will fully appear by a perusal of the following specification and claims.

The figure on the drawings is a vertical 55 section through my improved burner.

Referring now more particularly to the

characters of reference on the drawings, the numeral 1 designates the support for the vaporizing retort which may be of any desired structure. The vaporizing retort 2 60 may be of any desired form or dimensions found adaptable according to the use to which the burner is going to be put, and leading into the same is a fuel supply pipe 3. This pipe 3 may conduct the fuel into 65 the retort either by gravity or forced pressure, as may be desired. The pipe 3 may have a strainer 4 at an intermediate point to prevent solid matter from entering the retort.

70 The fuel passes into the retort 2, and heat is applied to the retort to that degree which will merely cause the fuel therein to vaporize. The rising vapors pass through a relatively large bypass 5 and thence through a 75 central outlet pipe 6 which passes downwardly through the retort 2 and is provided with a relatively large outlet nozzle 7. A tapered needle valve 8 controls the passage-way through the nozzle 7. This needle valve 80 8 has a shank 9 movable through a guide 10. On the lower end of the shank 9 is a ball 11 which engages a tapered valve stem 12 having an operating handle 13. By operating the handle 13, the position of the needle 85 valve 8 may be fixed.

At the base of the needle valve 8, at a considerable distance from the discharge nozzle 7, is a burner plate 14. The vapors passing through the nozzle 7 discharge 90 downwardly and strike the plate 14. The force of striking this plate 14 causes them to disseminate into the surrounding atmosphere where they are ignited by the flames of the burner.

95 As the fuel vapor passes out through the nozzle 7 it comes into immediate contact with a liberal supply of air, the atoms of carbon in the fuel then uniting with the oxygen of the air prior to ignition. This 100 forms as perfect a burning gas as can be produced in this type of device.

To gain the initial heat for the burner, an asbestos torch may be used or a small quantity of fuel may be placed on the plate 105 14 and ignited. As soon as the gas is generated, however, then the burner is self sustaining.

Having thus described my invention, what I claim as new and useful and desire to 110 secure by Letters Patent is:—

1. A hydrocarbon burner comprising a

burner, a liquid fuel retort positioned to be subjected to the heat of the burner, and a passageway leading from the top of the retort and passing over said top and then 5 down through the retort and terminating below the same, whereby the fuel vapors generated in the retort will discharge onto the burner before being subjected to any heat greater than the heat of the liquid fuel in 10 the retort.

2. A hydrocarbon burner comprising a retort, a nozzle arranged to discharge downwardly from the under side of the retort, means leading from the top of the retort to 15 the nozzle whereby the vapor from the retort may pass freely to the nozzle, a burner plate spaced below the discharge nozzle whereby such vapor will be forced from the nozzle against the plate and be then dis-

seminated from the plate prior to combustion, and a needle valve controlling the discharge nozzle, the plate being movable in the same relation as the needle valve. 20

3. A hydrocarbon burner comprising a retort, a central pipe projecting through the retort and having a lower discharge opening, the retort having a bypass at its upper end communicating with such pipe, a needle valve controlling the discharge opening, and a burner plate fixed to and movable with the 25 needle valve.

In testimony whereof I affix my signature in presence of two witnesses.

LOUIS E. TESTER.
